INVENTOR

UNITED STATES PATENT OFFICE

93,364

DESIGN FOR AN INDICATOR

Albert L. Stemwedel, Chicago, Ill., assignor, by direct and mesne assignments, of one-half to Fee and Stemwedel Inc., Chicago, Ill., and one-half to New Process Company, Warren, Pa., a corporation of Delaware

Application July 9, 1934, Serial No. 52,500

Term of patent 3½ years

To all whom it may concern:

Be it known that I, ALBERT L. STEMWEDEL, a citizen of the United States, residing at 219 West Chicago Avenue, in the county of Cook and State of Illinois, have invented a new, original, and ornamental Design for an Indicator, of which the following is a specification, reference being had to the accompanying drawing, forming part thereof.

The figure is a perspective view showing the front, side and top of the indicator.

I claim:

The ornamental design for an indicator as shown.

In witness whereof, I hereunto subscribe my name this 22nd day of June, 1934.

ALBERT L. STEMWEDEL.
